UNITED STATES PATENT OFFICE.

HERBERT ALLEN WHEELER, OF ST. LOUIS, MISSOURI.

TILE-DIE.

SPECIFICATION forming part of Letters Patent No. 616,170, dated December 20, 1898.

Application filed June 20, 1898. Serial No. 684,020. (No model.)

To all whom it may concern:

Be it known that I, HERBERT ALLEN WHEELER, a citizen of the United States, residing at the city of St. Louis, in the State of Missouri, have invented certain new and useful improvements in dies for making clay shingles, tiles, blocks, and similar clay products of a sheet-like nature, of which the following is a full, clear, and exact description, such as will enable others skilled in the art to which it appertains to make and use the same.

My invention is an improvement in the die or mold for making uniform, homogeneous, unbroken sheets of clay for roofing-tiles, flooring-tiles, slabs, blocks, and similar products of a sheet-like nature; and it consists of the novel arrangements and combinations hereinafter set forth in the following specification and claims and illustrated by the accompanying drawings.

The die can be adapted to any of the usual designs of clay-working machinery that can form a stream of clay, as an auger-machine, plunger-machine, steam-press, or other devices that can force a sheet of plastic or tempered clay through a die. When such a stream of plastic clay is forced through an ordinary thin die or narrow slot, there is a strong tendency for the resulting sheet of clay to rag or tear on the edges from the differential speeds in the different parts of the sheet of clay in consequence of the variation in the friction, as the central portion moves faster than the sides of the clay in the usual forms of dies. This ragging or tearing or breaking of the continuity of the edges of the sheet is a grave defect, and my device is to not only overcome this evil, but also accomplish it in such a practical way as to reduce the cost of renewal and repairs incident to the use of the dies to a minimum by having the wearing parts easily accessible or on the outside of the machine and so designed as to be easily renewed.

As clays differ radically in their nature and physical character, which requires marked variations in their individual methods of manipulation, and as the same clay behaves very differently according as it is either freshly mined or weathered, which latter process renders it much more plastic, and also whether it is tempered soft or stiff, my improvements take cognizance of these varia-

tions, and my devices can be varied to meet the peculiarities of each kind of clay in its toughness and plasticity, as well as in the variations in the temper of the same clay, for as these properties of a clay vary the friction of the clay particles among themselves and in passing through the die will vary, and consequently call for variation in the devices for equalizing these differential frictions in order to produce a uniform, homogeneous, unbroken sheet of clay for subsequent use for roofing-tile, flooring-tile, kiln-tile, or other purposes.

With this object in view my invention consists of equalizing devices to produce uniform friction as the sheet of clay passes through the die or else adding variable friction-surfaces to such parts of the sheet of clay that tend to flow too fast or else relieving or easing upon such parts of the clay sheet that tend to flow too slow, according as the character and temper of the clay render either of these methods preferable, or using two or more of these methods in conjunction to secure a uniform unbroken sheet of clay.

With these objects in view my invention consists of the following devices, hereinafter described in detail and specifically set forth in the following specification and claims.

In the accompanying drawings similar letters refer to similar parts.

Figure 1 is a rear view of the intermediate clay-chamber between the machine and the die. Fig. 2 is a longitudinal section through said feeding or clay chamber and the die as designed for clays of marked plasticity, and Fig. 3 is a horizontal section or plan view of the same. Fig. 4 is a horizontal section of the die when the clay is not so plastic, and a central tongue is extended out from the upper and lower surfaces of the die to retard or hold back the faster-moving central portion of the stream of clay by increasing the friction-surface along this central portion of the stream of clay. Fig. 5 is a horizontal section of the die when the clay is still less plastic or when it is desired to work the clay very stiff, and therefore the retarding-tongue is still further lengthened than in Fig. 4, while Fig. 6 is a longitudinal section of the same, showing the devices for varying the friction on the stream of clay and for taking up the wear of

the elongated retarding-tongue. Fig. 7 is a rear view, Fig. 8 is a horizontal or sectional plan on the line A B, Fig. 9 is a longitudinal section on the line C D, and Fig. 10 is another longitudinal section on the line E F, of the die when the clay is so plastic that it is only necessary to relieve the friction of the corners of the die by replacing them with the conical enlargements o o to secure a uniform unbroken sheet of clay.

In Figs. 2 and 3 the die b has a larger entrance for the clay stream in the rear at c than at the discharge d, so that when the clay is discharged at the mouth of the die 15 at d the narrowing of the cross-section of the die from m m to n n and the consequent contraction in area of the clay stream equalizes the friction when the clay is freely plastic, so that it leaves the die in a uniform un- 20 broken sheet. The rate of contraction from m m to n n or the decrease in the cross-section of the die will vary with the plasticity and temper of the clay to be worked.

In Fig. 4 the die b has the lower and upper 25 faces prolonged into a tongue f, that should preferably terminate in a parabolic periphery, and the central portion of the clay sheet has to pass between these two tongues after it has passed beyond the corners of the die at 30 n n, so that the increased friction caused by these tongues equalizes the greater friction caused by the sides of the die when the clay is rather stiff, or not very plastic. When the clay is more stiff, or still less plastic, the 35 tongues f f are made still longer, as in Fig. 5, to still further increase the friction of the central portion of the clay sheet. As these long tongues are exposed to considerable wear and as they are liable to spring, 40 and hence not press firmly on the sheet of clay, special arms g g are attached to the die by lugs, bolts, screws, or other suitable devices, and from the outer ends of these arms regulating-screws h h can be screwed against 45 the outer ends of these tongues to make them retain their gage to prevent them from springing and to take up their wear from use. Lock-nuts i i and j j on each side of the screws h h hold the latter to their proper places and also 50 enable the screws to be set so as to press more strongly onto the sheet of clay by screwing these regulating-screws against the tongues. These regulating-screws, of which as many 55 can be used as found necessary, also permit the tongues to be made of sheet metal or thin lining material, as they prevent any springing or variation in the gage of the sheet of clay between the tongues, and thus enable the die to be cheaply made and easily and 60 quickly repaired.

When the clay is very plastic, so that there is not much friction in its passage through the die, the slightly-greater friction of the clay in passing through the corners of the die 65 or m m m n than along the central portion of the die is compensated by easing up or en-

larging the openings at the rear corners of the die by the conical enlargements o o, as shown in Figs. 7, 8, 9, and 10, as this enlargement reduces and relieves the excessive friction of the corners.

The die b can be lined with liners c to take up the wear of the die and also enable it to be easily and cheaply repaired or restored to gage as it wears from use.

The feeding-chamber a, between the die b and the clay-machine, may be made of any suitable size or shape to fit the delivery of the clay-machine, the plasticity of the clay, and the size of the die to be used. It is preferably divided into halves, or two pieces, for convenience, and by lugs or flanges it is bolted onto the clay-machine and has lugs or flanges for permitting the die to be bolted or screwed or keyed onto it.

The die b is shown solid or in one piece; but it can also be divided into halves or two pieces, which enables the wear to be easily taken up if it is not lined with removable liners. The die can also be cored out or bored 90 out with chambers or passages for steam-jacketing to still further decrease the risk of ragging or breaking of the sheet of clay in passing through the die.

Where different kinds of clay are used, or 95 where different degrees of tempering of the same clay are worked, or where the least trouble in overcoming the tendency to ragging is desired, the die can be made with the contraction from e to d, with the corners relieved by the large conical enlargements o o, and with the retarding-surfaces to the faster-moving central portion of the clay sheet extended as in Figs. 5 and 6, and having the adjusting-screws h h for regulating these retarding-tongues and taking up their wear. If 100 there is not so much variation as to require these three methods jointly, two of them may be used, as found desirable for the clay, as all such mechanical devices should be modified to suit the peculiarities of each individual clay.

Having thus described my invention, what I claim, and desire to secure by Letters Patent, is—

1. An improved die having its upper and lower surfaces extended to form a pair of retarding-surfaces, with adjusting-screws to regulate said extended retarding-surfaces, with lock-nuts to hold said adjusting-screws, 120 with arms to carry said adjusting-screws and lock-nuts, substantially as shown.

2. An improved die with a contracted discharge, with the upper and lower surfaces extended beyond said contracted discharge to 125 form a pair of retarding-surfaces, with a pair of adjusting-screws to regulate said retarding-surfaces, with lock-nuts to control said adjusting-screws, with arms to carry said adjusting-screws and nuts, substantially as shown 130 and described.

3. The combination, in an improved die, of

a pair of arms carrying adjusting-screws, with lock-nuts to control said adjusting-screws, with extended retarding-surfaces from the upper and lower surfaces of said die that are 5 regulated by said adjusting-screws, with said die having a contracted discharge, with the corners in the rear of said die enlarged into

conical, converging surfaces, substantially as shown and described.
